Primary Examiner — Eric Goodman*Assistant Examiner* — Bao-Yen Nguyen(74) *Attorney, Agent, or Firm* — Dugan & Dugan, PC(57) **CLAIM**

The ornamental design for a gas diffuser assembly, as shown and described.

DESCRIPTION

FIG. 1 is a side elevational view of a gas diffuser assembly showing our new design, the opposite side being a mirror image thereof;

FIG. 2 is a bottom view thereof;

FIG. 3 is a top view thereof; and,

FIG. 4 is a front elevational view, the opposite (back) side being a mirror image thereof.

In all views, the broken lines depict portions of the article that form no part of the claimed design.

1 Claim, 2 Drawing Sheets(56)
